Primary Examiner — Antoine Duval Davis

(74) Attorney, Agent, or Firm — Boyle Fredrickson S.C.

(57) **CLAIM**The ornamental design of a torpedo level, as shown and
described.

DESCRIPTION

FIG. 1 is an isometric view of a torpedo level incorporating
our new design, wherein the portions in phantom form no
part of the claimed design;

FIG. 2 is a first side elevation view thereof;

FIG. 3 is a second side elevation view thereof;

FIG. 4 is a top plan view thereof;

FIG. 5 is a bottom plan view thereof;

FIG. 6 is a first end elevation view thereof; and,

FIG. 7 is a second end elevation view thereof.

1 Claim, 7 Drawing Sheets(56)
